JOSEPH DETHIER, OF BRUSSELS, BELGIUM

REGULATOR FOR WINDING ON INSTALLATIONS

Application filed July 8, 1930, Serial No. 466,570, and in France July 10, 1929.

This invention relates to a regulator for self-acting mules.

A self-acting mule comprises fixed parts such as the headstock and the creel for carrying the spools of roving, and a movable part such as the carriage for supporting a row of spindles inclined to the vertical and towards the creel, and travelling to and fro, from the creel to the front of the headstock (run-out of carriage) and back to the creel (run-in of carriage).

The spindles are rotated by the tin roller. On the carriage and in proximity to the spindles are also mounted members called the winding faller and the counter faller, keyed on shafts parallel to the direction of the row of spindles and called winding faller and counter faller shafts.

The roving coming from each spool passes between feed rollers mounted on a fixed part rigid with the creel and is then secured to the lower part of the spindle and wound for a few turns as far as the point of the latter.

When the carriage runs out, the feed rollers turn and deliver the slivers to the corresponding spindles which turn rapidly. As, however, the spindles are inclined to the vertical, the slivers cannot wind on them but jump over and become twisted and they are at the same time drawn out in view of the fact that the speed of delivery of the said rollers is lower than the speed of outward run of the carriage. The carriage reaches the front of the headstock and stops. Backing-off is then effected; that is, the spindles turn in the opposite direction in order to unwind the few turns which have previously been wound on them; but in order to prevent these

threads from kinking or forming snarls, the supplementary length coming from the unwound part is taken up between the winding faller and the counter faller in the following manner; during the run-out of the carriage, the winding faller and the counter faller have no action on the yarn and are arranged so that the winding faller is above the yarn proceeding from the feed rollers to the spindles and the counter faller is below the said yarn. When backing-off, the wind-

ing faller descends and the counter faller rises, and consequently they tension the threads. When the backing-off is terminated, the counter faller is free and its position is determined by the tension in the threads with which it comes into contact.

The winding-on then takes place. The carriage runs in and the spindles are driven by the tin roller in the direction of rotation they followed during the outward run of the carriage and they wind on themselves the threads guided by the winding faller and the counter faller.

The length of thread comprised between the winding faller and the counter faller during winding-on is called the reserve. Almost at the end of the winding-on, the winding faller and the counter faller return to their inoperative position corresponding to the outward run of the carriage, and the reserve which is left to itself winds on the spindle from the point at which the last turn is wound as far as the point of the spindle. This reserve diminishes as the cop is formed, since the free length of the spindle diminishes more and more. While becoming less, however, this reserve must remain "normal" at all stages of the formation of the cop; that is, for a given layer of yarn to be wound on the spindle, the reserve must neither increase beyond the value appropriate to this particular stage which would produce snarls in the thread, nor decrease beyond the value which would stretch or break the yarn.

The rotation of the spindles is controlled during the winding-on operation by a member called the quadrant, provided with an arm upon which is situated a member called the "nut", to which is connected the winding chain, which latter is wound upon a drum through which the tin roller is driven.

As the cop increases in size, the diameter increases, and thus, for one and the same length or delivery to be wound on, the spindles must make fewer revolutions and the nut must consequently rise on the quadrant arm. But if the nut rises by too large an amount, the number of turns of the spindle decreases, and as the length of delivery to be wound on is constant, the reserve increases,

thus producing snarls in the threads; if the nut rises by too small an amount under the above conditions, the reserve decreases and the threads break.

5 The object of the invention is thus to provide a regulator, the object of which is to make the reserve maintain its normal value for each delivery, and for this purpose the said regulator makes the above-mentioned 10 nut descend when the reserve increases above the normal value and makes it rise when the reserve falls beyond the said value.

However, as stated above, after backing-off, the counter faller is free and its position is determined solely by the tension of 15 the threads. Consequently the counter faller which, when the reserve increases or decreases, varies the position of the quadrant screw, must have its action on this screw controlled.

For this purpose, according to the invention, a system of cams is keyed on the shaft of the winding faller. The first cam controls the action of the counter faller on the 20 screw when the latter must rise, and the second cam controls the action of the counter faller on the screw when the latter must descend.

The accompanying drawings illustrate, by 25 way of example, and in a non-limiting manner, one form of construction of the invention.

Figure 1 is a view of the mule fitted with the regulator according to the invention.

30 Figure 2 is an enlarged view of the regulator according to the invention.

The self-acting mule shown in Fig. 1 comprises fixed parts such as headstock 15a, 15b, a creel (not shown) which carries the spools 40 of roving, and a movable part, the carriage 10, supporting a row of spindles such as 2 inclined to the vertical and towards the back of the headstock 15a, and traversed by means of wheels, alternatively from the back of the 45 headstock 15a to the front 15b (run-out of carriage) and from the front 15b to the back of the headstock 15a (run-in of carriage).

In proximity to the above-mentioned row 50 of spindles and carried by the carriage is situated a member 5 called the winding faller and a member 7 called the counter faller which are keyed, respectively, on the winding faller shaft 5a and the counter faller shaft 7a, the function of which will be described 55 hereinafter.

The roving coming from each spool mounted on the creel passes between the feeding and drawing rollers 2a and from there is attached to the lower part of its spindle and 60 wound for some turns as far as the point of the latter.

When the carriage 10 runs out, the feeding and drawing rollers turn and deliver the rovings to their corresponding spindles 2 which 65 turn rapidly, being driven by a tin roller 4e

carried by the carriage 10 and driving the spindles by means of a cord 4d passing over a whorl 4c keyed on each spindle. However, on account of the fact that the spindles are inclined to the vertical, the yarns jump 70 over the point of the spindles and, consequently, each time they jump they receive a twist. The carriage continues to move away from the back of the headstock 15a, and as the feeding and drawing rollers 2a have a 75 speed of delivery which is less than the speed of run-out of the carriage, the rovings are drawn and at the same time twisted and become yarn.

The carriage 10 reaches the front of the headstock 15b and stops. Backing-off then takes place, that is, the spindles 2 make a few revolutions in the opposite direction to the previous one in order to unwind the few turns of yarn previously wound on the spindles, and in order to prevent these threads from slackening and forming snarls, the length unwound is taken up between the winding faller 5 and the counter faller 7 in the following manner: During the run-out 85 of the carriage, the winding faller and the counter faller occupy the position shown in Fig. 1, that is, they have no action on the thread proceeding from the feed rollers 2a to the spindles, because the winding faller is above the threads and the counter faller is below them. When backing-off takes place, the winding faller descends and the counter faller rises and, consequently, they take up 90 the length of backed-off yarn and tension the 95 threads.

When the backing-off is completed, the counter faller takes up a position determined solely by its contact with the threads which it tensions by means of a counterweight (not 100 shown).

The threads are then wound on the spindles. The carriage 10 runs in towards the back of the headstock 15a, the spindles are driven by the tin roller in the direction of 110 rotation which they had during the run-out of the carriage, and the threads are wound on them guided by the winding faller and the counter faller.

During the winding-on, the spindles are 115 driven by the tin roller which is operated in the following manner: A quadrant 16d provided with an arm 16f is mounted on the front of the headstock 15b and is pivoted on the latter at 16b. This arm is traversed 120 by a screw 12a along which moves a nut 12c connected by a chain 16g to the drum 4g upon which it is wound. This drum is rigid with a pinion 4h meshing with a pinion 4f keyed upon the tin roller 4e. During the 125 winding-on, the carriage 10 approaches the back of the headstock 15a and the quadrant 16d swings towards the back of the headstock 15a under a control (not shown).

As a result of the two above-mentioned 130

movements, the chain 16_g unwinds from the barrel 4_g and produces the rotation of the tin roller and, consequently, of the spindles. It will be understood that the number of 5 turns of the spindles during winding-on is a function of the length of chain unwound from the barrel and that this depends upon the position of the nut 12_c on the screw 12_a. Moreover, as the cop is formed on the spindle its diameter increases, and as the length to be wound on is constant, the spindles must make less turns, so that the nut must rise little by little on the screw 12_a.

The length of yarn comprised between 15 the winding faller and the counter faller during winding-on is called the reserve which, at the end of the winding-on operation, must wind on the spindle from the last turn wound on the latter as far as the 20 point of the spindle. This reserve must decrease as the cop is formed since the length of free spindle decreases. But this reserve must, for each amount to be wound on, have a normal value, that is, a clearly determined 25 value; in other words, it must not be too great, because the yarn wound on would become too loose and would form snarls, or too short because the yarn to be wound would break. This result is obtained by 30 correcting the accidental variations in reserve by means of a regulator which makes the nut 12_c rise on the screw 12_a if the reserve is too small and makes the nut descend if the reserve is too great.

35 These variations in reserve produce variations in position of the counter faller, but as hereinbefore stated, the counter faller is perfectly free after the backing-off operation. Now the reserve diminishes as the 40 formation of the cop progresses; consequently, the counter faller which, when the reserve increases or decreases, varies the position of the quadrant screw must have its action on this screw controlled. For this 45 purpose a system of cams 5_m, 5_n—5_{m₂} is keyed on the shaft 5_a of the winding faller; the cam 5_m will make the quadrant nut rise when necessary and the cam 5_n—5_{m₂} will make it descend when necessary.

50 A roller 7_t bears against the cam 5_m. This roller is mounted on a lever 7_p pivoted at 0₃ on an arm 7_r supported on the shaft 7_a on the counter faller 7. The left end of the lever 7_p is connected to a rod 7_f connected 55 by the lever 7_g, pivoted at 7_h, to the brake band 7_h which surrounds a pulley 7_m carried by the carriage 10. The cam 5_m comprises a profile portion 5_{m₁} of constant radius and a portion 5_p, pivoted at 0, of increasing radius in a counter-clockwise direction.

The cam 5_n supported on the shaft 5_a of the faller 5 includes a portion *a*—*b* of its profile which increases in height from *a* to *b*, 60 and a portion *b*—*c* which decreases from *b*

to *c*. The point *a* of this cam corresponds to the lowest position of the faller during the unwinding of the first spindle; the point *b* corresponds to the highest position of the faller during the unwinding of the last draw 70 or stretch; the points between *a* and *b* correspond to the different successive positions of the faller 5 during the formation of the cop. Finally, the point *c* corresponds to the invariable upper position of rest of the faller 5 during the running-out of the carriage. Against this cam 5_n bears a roller 7_v carried by a cam 5_{m₂} pivoted at 0₂ on a member 8_v freely mounted on the shaft 5_a and embracing the shaft of the counter-faller 7 with its notch 8_w (Fig. 2). The cam 5_{m₂} has a profile portion *h*—*f* of constant radius and a portion *f*—*g* of decreasing radius from *f* to *g*. Against the cam 5_{m₂} bears a roller 7_u mounted at one end of a lever 7_q pivoted at 0₄ on an arm 7_s mounted on the shaft 7_a of the counter faller 7. The left end of this lever is connected to a rod 8_f connected by the lever 8_g, pivoted at 8_h, to the brake band 8_h which surrounds a pulley 8_m carried by 85 the carriage 10.

Further, the strands 9_a and 9_b of an endless chain pass over the pulleys 7_m and 8_m; this chain extends on the one hand over a loose pulley 9_d on the back of the headstock 15_a and also over a pulley 16_m loose upon the shaft 16_n but adapted to be made rigid with a pulley 9_c by a well-known dog clutch placed under the control of a lever 11_b, connected to a lever 11 upon which are arranged 90 the stops 11_a and 11_c.

At the lower part of the carriage 10 are also keyed stops 10_c and 10_d; the stop 10_d can pivot about 0 to the left from its position of rest but cannot swing to the right on account of the presence of the stop B, keyed to the carriage. This pulley 9_c, by means of a chain 16_p, controls the rotation of the screw 12_a by means of bevel pinions. Moreover, the strand 9_a of the chain carries a stop 9_f and the strand 9_b, a stop 9_h, these stops being situated one vertically below the other when the reserve is normal.

Let us now assume that the cop is commenced and that the carriage runs out. The brakes mounted on the latter are open and, consequently, the pulleys 7_m and 8_m run over the strands of the endless chain without driving them. The carriage reaches the front of the headstock; backing-off takes place, and the winding faller and counter faller come into contact with the threads. In view of the fact that the first layer of yarn is about to be wound on, the winding faller has descended to its lowest position.

After the backing-off, winding-on takes place; the counter faller slightly rises in a counter-clockwise direction to come into contact with the threads, and the arm 7_r also 130

pivots in a counter-clockwise direction. This produces a slight descent of the left end of the lever $7p$ and a slight descent of the rod $7f$. The faller 5 descends rapidly from its 5 invariable upper position of rest, to wind the descending roving of thread on the spindle. The faller 5 then successively and rapidly presents to the roller $7t$ a constant radius $5m_1$, then an increasing radius $5p$, so that 10 when the faller is in its lower position, the roller $7t$ is in its lowest position. This descent of the roller thus produces a corresponding rise of the rod $7f$.

The counter faller 7 guided by the thread 15 continues to rise and this results in a new descent of the rod $7f$. Then the faller 5 slowly rises to re-wind the ascending roving of thread on the spindle. The faller 5 presents to the roller $7t$ a smaller and smaller 20 radius; the roller rises and causes the rod $7f$ to descend. The up-and-down movements of the rod $7f$ finally result in a slight descent of the rod $7f$ which permits the corresponding 25 brake band to be inoperative on the pulley $7m$.

As for the rod $8f$ and its brake, the counter faller 7 slightly rises in the counter-clockwise direction as before, and this results in a slight descent of the rod $8f$. The faller 5 descends 30 rapidly as in the preceding case and the cam $5m$ presents to the roller $7v$ a smaller and smaller radius; then in its turn the cam $5m_2$ presents to the roller $7u$ an equally smaller and smaller radius. This results in a descent 35 of the left end of the lever $7q$ and a descent of the rod $8f$.

The counter faller 7 guided by the threads continues to rise in a counter-clockwise direction and this results in a new descent of the 40 rod $8f$. Then the faller 5 rises to re-wind the ascending roving of thread. The roller $7v$ is in contact with a larger and larger radius of the cam $5n$, which leads the roller $7u$ into contact with a greater and greater 45 radius of the cam $5m_2$. This results in a descent of the roller $7u$ and a rise of the left end of the lever $7q$ and a rise of the rod $8f$. These up-and-down movements of the rod $8f$ result in a descent of the rod $8f$, which 50 descent is insufficient to operate the brake band $8h$ on the pulley $8m$. If at this stage in the formation of the cop, the reserve has the value it should have, then during the run-in of the carriage, the winding faller and the counter faller gradually return to their original position and the brakes will 55 not have acted.

Suppose that there is a diminution in 60 length of the reserve at this stage of the formation of the cop, that is, during the formation of the core or base of the cop. As already explained, the rises of the counter faller 7 produce a slight descent of the rod $7f$, and the descent and the rise of the faller 65 5 result, respectively, in a rise and descent

of the rod $7f$. But since there is a diminution of the reserve, the counter faller 7 again descends in a clockwise direction, and its descent results in a rise of the left end of the lever $7p$ and a rise of the rod $7f$. The rod $7f$ is then submitted to a slight descent and a great rise, in consequence of which it acts on its brake band to stop the rotation of the pulley $7m$, thus locking against rotation the pulley $7m$, whereby the strand $9a$ of the 70 endless chain is driven towards the back of the headstock by the carriage, this drive continuing as long as the reduction in reserve 75 persists.

The following takes place in the same conditions of diminution of reserve for the rod $8f$ and its corresponding brake band: as already explained, the rises of the counter faller 7 produce a descent of the rod $8f$. The rise and the descent of the faller 5 effect in 80 this rod $8f$ movements in the opposite direction, the amplitudes of which neutralize each other. Finally, the rod $8f$ is lowered. Since the reserve is reduced, the counter faller 7 again descends in a clockwise direction, 85 which corresponds to the rise of the rod $8f$. That is, the rod $8f$ is submitted to a rise and to a fall, the amplitudes of which neutralize each other or nearly so, and the corresponding brake is rendered inoperative on 90 the pulley. When the carriage reaches the back of the headstock, the winding faller and counter faller return to their original position.

When the following run-out takes place, 100 the carriage 10 abuts against the stop $9f$ and drives it towards the front of the headstock, and after the moment when the stop $10c$ on the carriage encounters the stop $11a$ and the lever 11 is moved towards the headstock, the roller $16m$ and the pulley $9c$ are coupled together by the dog-clutch whereby the screw $12a$ is rotated by the chain $16p$ in the direction corresponding to an upward movement of the nut $12c$.

In this manner the number of turns of the spindles decreases during the following winding-on operation and the reserve returns to the value it must have at this stage in the formation of the cop. When the carriage 110 returns, the stop $10d$ urges the stop $11c$ towards the back of the headstock so that $9c$ and $16n$ are declutched.

Suppose there is an increase in value of 115 the reserve during the formation of the body of the cop. Since the re-winding is effected in proportion as the faller 5 descends less and less low, the cams $5m$ and $5n$ will effect revolutions of smaller and smaller angular amplitude. It is evident that only the portion $5m_1$ will be in contact with the roller $7u$.

The normal rises of the counter faller 7 produce slight descents of the rod $7f$. Then when the faller 5 descends, as one draw or stretch of the body of the cop is wound, only 120 125 130

the portion $5m_1$ of constant radius of the cam $5m$ will be in contact with the roller $7t$. Consequently, the descent and the rise of the faller 5 leave the position of the roller $7t$ unchanged. Since there is an increase in reserve, the counter faller 7 abnormally rises in a counter-clockwise direction, which accelerates the descent of the rod $7f$ and renders its corresponding brake inoperative on the pulley $7m$.

The ascents of the counter faller 7 produce a descent of the rod $8f$, and as the roller $7u$ is in contact with the profile $f-h$, its position will remain invariable. When the increase in reserve is effected, the counter faller 7 will rise abnormally and increase the descent of the rod $8f$, while the brake $8h$ prevents rotation of the pulley $8m$.

Further, when dealing with very fine counts, the stop $11c$ is brought nearer to the stop $11a$ in order to reduce the action of the cams on the quadrant screw; the contrary is effected in the case of coarse counts.

I claim:

- 25 1. In a self-acting mule composed of a carriage having an outward run and an inward run relative to a fixed part of the mule, spindles mounted on the carriage and on which threads may be wound, means for producing by the displacement of the carriage the rotation of the spindles when the said carriage is displaced in the direction of the inward run, a faller for guiding the threads on to the spindles during the inward run, a counter faller tending to tension the threads during the said inward run, a sector pivoted on a fixed part of the mule, a screw moving along an arm of said sector and acting, during its displacement on the means for rotating the spindles, to vary the speed of the latter, two pulleys mounted on fixed parts of the mule, an endless chain each run of which is supported by one of the said pulleys, means for displacing each belt in accordance with the displacement of the carriage, and means for connecting one of the two said pulleys to the screw of the sector in order to change the rotation of the said pulley into displacement of the said screw.
- 30 2. In a self-acting mule composed of a carriage having an outward run and an inward run relative to a fixed part of the mule, spindles mounted on the carriage and on which threads may be wound, means for producing by the displacement of the carriage the rotation of the spindles when the said carriage is displaced in the direction of the inward run, a faller for guiding the threads on to the spindles during the inward run, a counter faller tending to tension the threads during the said inward run, a sector pivoted on a fixed part of the mule, a screw moving along an arm of said sector and acting, during its displacement on the means for rotating the spindles, to vary the speed of the latter, two pulleys loosely mounted on fixed parts of the mule, an endless chain each run of which is supported by one of the said pulleys, the pulleys being put in rotation by each of the said belts, means for braking the rotation of one or the other of these pulleys in function of the variation of the length of reserve, and means for changing the registered variations into displacements of the screw of the sector.
- 35 3. In a self-acting mule composed of a carriage having an outward run and an inward run relative to a fixed part of the mule, spindles mounted on the carriage and on which threads may be wound, means for producing by the displacement of the carriage the rotation of the spindles when the said carriage is displaced in the direction of the inward run, a faller for guiding the threads on to the spindles during the inward run, a counter faller tending to tension the threads during the said inward run, a sector pivoted on a fixed part of the mule, a screw moving along an arm of said sector and acting, during its displacement on the means for rotating the spindles, to vary the speed of the latter, two pulleys mounted on fixed parts of the mule, an endless chain each run of which is supported by one of the said pulleys, means for displacing each belt in accordance with the displacement of the carriage, and means for connecting one of the two said pulleys to the screw of the sector in order to change the rotation of the said pulley into displacement of the said screw.
- 40 4. In a self-acting mule composed of a carriage having an outward run and an inward run relative to a fixed part of the mule, spindles mounted on the carriage and on which threads may be wound, means for producing by the displacement of the carriage the rotation of the spindles when the said carriage is displaced in the direction of the inward run, a faller for guiding the threads on to the spindles during the inward run, a counter faller tending to tension the threads during the said inward run, a sector pivoted on a fixed part of the mule, a screw moving along an arm of said sector and acting, during its displacement on the means for rotating the spindles, to vary the speed of the latter, two pulleys mounted on fixed parts of the mule, an endless chain each run of which is supported by one of the said pulleys, means for displacing each belt in accordance with the displacement of the carriage, and means for connecting one of the two said pulleys to the screw of the sector in order to change the rotation of the said pulley into displacement of the said screw.
- 45 5. In a self-acting mule composed of a carriage having an outward run and an inward run relative to a fixed part of the mule, spindles mounted on the carriage and on which threads may be wound, means for producing by the displacement of the carriage the rotation of the spindles when the said carriage is displaced in the direction of the inward run, a faller for guiding the threads on to the spindles during the inward run, a counter faller tending to tension the threads during the said inward run, a sector pivoted on a fixed part of the mule, a screw moving along an arm of said sector and acting, during its displacement on the means for rotating the spindles, to vary the speed of the latter, two pulleys mounted on fixed parts of the mule, an endless chain each run of which is supported by one of the said pulleys, means for displacing each belt in accordance with the displacement of the carriage, and means for connecting one of the two said pulleys to the screw of the sector in order to change the rotation of the said pulley into displacement of the said screw.
- 50 6. In a self-acting mule composed of a carriage having an outward run and an inward run relative to a fixed part of the mule, spindles mounted on the carriage and on which threads may be wound, means for producing by the displacement of the carriage the rotation of the spindles when the said carriage is displaced in the direction of the inward run, a faller for guiding the threads on to the spindles during the inward run, a counter faller tending to tension the threads during the said inward run, a sector pivoted on a fixed part of the mule, a screw moving along an arm of said sector and acting, during its displacement on the means for rotating the spindles, to vary the speed of the latter, two pulleys mounted on fixed parts of the mule, an endless chain each run of which is supported by one of the said pulleys, means for displacing each belt in accordance with the displacement of the carriage, and means for connecting one of the two said pulleys to the screw of the sector in order to change the rotation of the said pulley into displacement of the said screw.
- 55 7. In a self-acting mule composed of a carriage having an outward run and an inward run relative to a fixed part of the mule, spindles mounted on the carriage and on which threads may be wound, means for producing by the displacement of the carriage the rotation of the spindles when the said carriage is displaced in the direction of the inward run, a faller for guiding the threads on to the spindles during the inward run, a counter faller tending to tension the threads during the said inward run, a sector pivoted on a fixed part of the mule, a screw moving along an arm of said sector and acting, during its displacement on the means for rotating the spindles, to vary the speed of the latter, two pulleys mounted on fixed parts of the mule, an endless chain each run of which is supported by one of the said pulleys, means for displacing each belt in accordance with the displacement of the carriage, and means for connecting one of the two said pulleys to the screw of the sector in order to change the rotation of the said pulley into displacement of the said screw.
- 60 8. In a self-acting mule composed of a carriage having an outward run and an inward run relative to a fixed part of the mule, spindles mounted on the carriage and on which threads may be wound, means for producing by the displacement of the carriage the rotation of the spindles when the said carriage is displaced in the direction of the inward run, a faller for guiding the threads on to the spindles during the inward run, a counter faller tending to tension the threads during the said inward run, a sector pivoted on a fixed part of the mule, a screw moving along an arm of said sector and acting, during its displacement on the means for rotating the spindles, to vary the speed of the latter, two pulleys mounted on fixed parts of the mule, an endless chain each run of which is supported by one of the said pulleys, means for displacing each belt in accordance with the displacement of the carriage, and means for connecting one of the two said pulleys to the screw of the sector in order to change the rotation of the said pulley into displacement of the said screw.
- 65 9. In a self-acting mule composed of a carriage having an outward run and an inward run relative to a fixed part of the mule, spindles mounted on the carriage and on which threads may be wound, means for producing by the displacement of the carriage the rotation of the spindles when the said carriage is displaced in the direction of the inward run, a faller for guiding the threads on to the spindles during the inward run, a counter faller tending to tension the threads during the said inward run, a sector pivoted on a fixed part of the mule, a screw moving along an arm of said sector and acting, during its displacement on the means for rotating the spindles, to vary the speed of the latter, two pulleys mounted on fixed parts of the mule, an endless chain each run of which is supported by one of the said pulleys, means for displacing each belt in accordance with the displacement of the carriage, and means for connecting one of the two said pulleys to the screw of the sector in order to change the rotation of the said pulley into displacement of the said screw.

threads may be wound, means for producing by the displacement of the carriage the rotation of the spindles when the said carriage is displaced in the direction of the inward run, a faller for guiding the threads on to the spindles during the inward run, a counter faller tending to tension the threads during the said inward run, a sector pivoted on a fixed part of the mule, a screw moving along an arm of said sector and acting, during its displacement on the means for rotating the spindles, to vary the speed of the latter, two pulleys loosely mounted on fixed parts of the mule, an endless chain each run of which is supported by one of the said pulleys, the pulleys being put in rotation by each of the said belts, a lever connected at one of its ends to a brake acting on one of the pulleys, the other end of the lever being displaced in accordance with the variations of reserve in a determined direction, means for rendering the displacements of the said lever proportional to the position of the counter faller, and means for rendering these displacements subordinate to the position of the faller in order to produce a progressive decrease of the reserve during the formation of the bobbin.

6. In a self-acting mule composed of a carriage having an outward run and an inward run relative to a fixed part of the mule, spindles mounted on the carriage and on which threads may be wound, means for producing by the displacement of the carriage the rotation of the spindles when the said carriage is displaced in the direction of the inward run, a faller for guiding the threads on to the spindles during the inward run, a counter faller tending to tension the threads during the said inward run, a sector pivoted on a fixed part of the mule, a screw moving along an arm of said sector and acting, during its displacement on the means for rotating the spindles, to vary the speed of the latter, two pulleys loosely mounted on fixed parts of the mule, an endless chain each run of which is supported by one of the said pulleys, the pulleys being put in rotation by each of the said belts, a lever connected at one of its ends to a brake acting on one of the pulleys, the other end of the lever being displaced in accordance with the variations of reserve in a determined direction, an arm integral with the axis of the counter faller and connected with the said lever, and means for rendering these displacements subordinate to the position of the faller in order to produce a progressive decrease of the reserve during the formation of the bobbin.

7. In a self-acting mule composed of a carriage having an outward run and an inward run relative to a fixed part of the mule, spindles mounted on the carriage and on which threads may be wound, means for producing by the displacement of the carriage the rotation of the spindles when the said carriage

is displaced in the direction of the inward run, a faller for guiding the threads on to the spindles during the inward run, a counter faller tending to tension the threads during the said inward run, a sector pivoted on a fixed part of the mule, a screw moving along an arm of said sector and acting, during its displacement on the means for rotating the spindles, to vary the speed of the latter, two pulleys loosely mounted on fixed parts of the mule, an endless chain each run of which is supported by one of the said pulleys, the pulleys being put in rotation by each of the said belts, means for braking the rotation of one or the other of these pulleys in function of the variation of the length of reserve, means for changing the registered variations into displacements of the screw of the sector, and two distinct connections between the faller and the counter faller acting during variations of the length of reserve respectively on each of said pulleys.

8. In a self-acting mule composed of a carriage having an outward run and an inward run relative to a fixed part of the mule, spindles mounted on the carriage and on which threads may be wound, means for producing by the displacement of the carriage the rotation of the spindles when the said carriage is displaced in the direction of the inward run, a faller for guiding the threads on to the spindles during the inward run, a counter faller tending to tension the threads during the said inward run, a sector pivoted on a fixed part of the mule, a screw moving along an arm of said sector and acting, during its displacement on the means for rotating the spindles, to vary the speed of the latter, two pulleys loosely mounted on fixed parts of the mule, an endless chain each run of which is supported by one of the said pulleys, the pulleys being put in rotation by each of the said belts, means for braking the rotation of one or the other of these pulleys in function of the variation of the length of reserve, a system of cams belonging to each of the said connections and displaced in function of the variations of the faller and the counter faller, a pivoting lever around an arm fixed to the counter faller and leaning at one of its ends on the said system of cams and in connection at the other end with the means for registering the variations of length of reserve, and means for changing the registered variations into displacements of the screw of the sector.

9. In a self-acting mule composed of a carriage having an outward run and an inward run relative to a fixed part of the mule, spindles mounted on the carriage and on which threads may be wound, means for producing by the displacement of the carriage the rotation of the spindles when the said carriage is displaced in the direction of the inward run, a faller for guiding the threads on to

the spindles during the inward run, a counter faller tending to tension the threads during the said inward run, a sector pivoted on a fixed part of the mule, a screw moving 5 along an arm of said sector and acting, during its displacement on the means for rotating the spindles, to vary the speed of the latter, two pulleys loosely mounted on fixed parts of the mule, an endless chain each run 10 of which is supported by one of the said pulleys, the pulleys being put in rotation by each of the said belts, means for braking the rotation of one or the other of these pulleys in function of the variation of the length of 15 reserve, a system of cams belonging to each of the said connections and displaced in function of the variations of the faller and the counter faller, a pivoting lever around an arm fixed to the counter faller and leaning at 20 one of its ends on the said system of cams and in connection at the other end with the means for registering the variations of length of reserve, means for changing the registered variations into displacements of the screw 25 of the sector, and means for rendering the system of cams adjustable.

10. In a self-acting mule composed of a carriage having an outward run and an inward run relative to a fixed part of the mule, 30 spindles mounted on the carriage and on which threads may be wound, means for producing by the displacement of the carriage the rotation of the spindles when the said carriage is displaced in the direction of 35 the inward run, a faller for guiding the threads on to the spindles during the inward run, a counter faller tending to tension the threads during the said inward run, a sector pivoted on a fixed part of the mule, a screw moving 40 along an arm of said sector and acting, during its displacement on the means for rotating the spindles, to vary the speed of the latter, two pulleys loosely mounted on fixed parts of the mule, an endless chain each run 45 of which is supported by one of the said pulleys, the pulleys being put in rotation by each of the said belts, means for braking the rotation of one or the other of these pulleys in function of the variation of the length of 50 reserve, means for changing the registered variations into displacements of the screw of the sector, a connection adapted to correct the decreases of the length of reserve and acting in two stages, one variable stage corresponding to the formation of the lower conical part of the bobbin, and the other stage corresponding to the formation of the cylindrical 55 part.

12. In a self-acting mule composed of a carriage having an outward run and an inward run relative to a fixed part of the mule, 60 spindles mounted on the carriage and on which threads may be wound, means for producing by the displacement of the carriage the rotation of the spindles when the said carriage is displaced in the direction of the inward run, a faller for guiding the threads on to the spindles during the inward run, a counter faller tending to tension the threads during the said inward run, a sector pivoted on a fixed part of the mule, a screw moving 65 along an arm of said sector and acting, during its displacement on the means for rotating the spindles, to vary the speed of the latter, two pulleys loosely mounted on fixed parts of the mule, an endless chain each run 70 of which is supported by one of the said pulleys, the pulleys being put in rotation by each of the said belts, means for braking the rotation of one or the other of these pulleys in function of the variation of the length of 75 reserve, means for changing the registered variations into displacements of the screw of the sector, a connection adapted to correct the decreases of the length of reserve and acting in two stages, one variable stage corresponding to the formation of the lower conical part of the bobbin, and the other stage corresponding to the formation of the cylindrical 80 part.

12. In a self-acting mule composed of a carriage having an outward run and an inward run relative to a fixed part of the mule, 85 spindles mounted on the carriage and on which threads may be wound, means for producing by the displacement of the carriage the rotation of the spindles when the said carriage is displaced in the direction of the inward run, a faller for guiding the threads on to the spindles during the inward run, a counter faller tending to tension the threads during the said inward run, a sector pivoted on a fixed part of the mule, a screw moving 90 along an arm of said sector and acting, during its displacement on the means for rotating the spindles, to vary the speed of the latter, two pulleys loosely mounted on fixed parts of the mule, an endless chain each run 95 of which is supported by one of the said pulleys, the pulleys being put in rotation by each of the said belts, means for braking the rotation of one or the other of these pulleys in function of the variation of the length of 100 reserve, means for changing the registered variations into displacements of the screw of the sector, a connection adapted to correct the decreases of the length of reserve and acting in two stages, one variable stage corresponding to the formation of the lower conical part of the bobbin, and the other stage corresponding to the formation of the cylindrical 105 part.

12. In a self-acting mule composed of a carriage having an outward run and an inward run relative to a fixed part of the mule, 110 spindles mounted on the carriage and on which threads may be wound, means for producing by the displacement of the carriage the rotation of the spindles when the said carriage is displaced in the direction of the inward run, a faller for guiding the threads on to the spindles during the inward run, a counter faller tending to tension the threads during the said inward run, a sector pivoted on a fixed part of the mule, a screw moving 115 along an arm of said sector and acting, during its displacement on the means for rotating the spindles, to vary the speed of the latter, two pulleys loosely mounted on fixed parts of the mule, an endless chain each run 120 of which is supported by one of the said pulleys, the pulleys being put in rotation by each of the said belts, means for braking the rotation of one or the other of these pulleys in function of the variation of the length of 125 reserve, a connection adapted to correct the increases of reserve and acting in two stages, one stage during which the means for registering the variations of the length of reserve is inoperative, the said stage corresponding to the displacement of the faller in the interval between its upper invariable position of rest and its upper position of working, the other stage, during which the said means are operable, corresponding to the displacement of the faller in its zone of working, means for 130

13. In a self-acting mule composed of a carriage having an outward run and an inward run relative to a fixed part of the mule, spindles mounted on the carriage and on which threads may be wound, means for producing by the displacement of the car-

rendering this action active and inactive, and means for changing the registered variations into displacements of the screw of the sector.

13. In a self-acting mule composed of a carriage having an outward run and an inward run relative to a fixed part of the mule, spindles mounted on the carriage and on which threads may be wound, means for producing by the displacement of the carriage 5 the rotation of the spindles when the said carriage is displaced in the direction of the inward run, a faller for guiding the threads on to the spindles during the inward run, a counter faller tending to tension the threads 10 during the said inward run, a sector pivoted on a fixed part of the mule, a screw moving along an arm of said sector and acting, during its displacement on the means for rotating the spindles, to vary the speed of the 15 latter, two pulleys loosely mounted on fixed parts of the mule, an endless chain each run of which is supported by one of the said pulleys, the pulleys being put in rotation by each of the said belts, means for braking 20 the rotation of one or the other of these pulleys in function of the variation of the length of reserve, a cam integral with the axis of the faller and having two eccentricities of inverse direction, one eccentricity acting 25 during the displacement of the faller in the interval between its upper invariable position of rest and its upper position of work, the other eccentricity acting during the displacement of the faller corresponding 30 to the formation of the bobbin, and means for changing the registered variations into displacements of the screw of the sector.

14. In a self-acting mule composed of a carriage having an outward run and an inward run relative to a fixed part of the mule, spindles mounted on the carriage and on which threads may be wound, means for producing by the displacement of the carriage 40 the rotation of the spindles when the said carriage is displaced in the direction of the inward run, a faller for guiding the threads on to the spindles during the inward run, a counter faller tending to tension the threads during the said inward run, a sector pivoted 45 on a fixed part of the mule, a screw moving along an arm of said sector and acting, during its displacement on the means for rotating the spindles, to vary the speed of the latter, two pulleys loosely mounted on fixed 50 parts of the mule, an endless chain each run of which is supported by one of the said pulleys, the pulleys being put in rotation by each of the said belts, means for braking the 55 rotation of one or the other of these pulleys in function of the variation of the length of reserve, means for changing the registered variations into displacements of the screw of the sector, two distinct cams, one of which is fixed on the axis of the faller, the other 60 pivoting around a fixed point and leaning on 65

the first cam, and a roller in relation with one of the extremities of a lever connected with a brake acting on one of the pulleys and leaning against the second cam.

15. In a self-acting mule composed of a carriage having an outward run and an inward run relative to a fixed part of the mule, spindles mounted on the carriage and on which threads may be wound, means for producing by the displacement of the carriage 70 the rotation of the spindles when the said carriage is displaced in the direction of the inward run, a faller for guiding the threads on to the spindles during the inward run, a counter faller tending to tension the threads during the said inward run, a sector pivoted on a fixed part of the mule, a screw moving along an arm of said sector and acting, during its displacement on the means for 75 rotating the spindles, to vary the speed of the latter, two pulleys loosely mounted on fixed parts of the mule, an endless chain each run of which is supported by one of the said pulleys, the pulleys being put in rotation by each of the said belts, means for braking the 80 rotation of one or the other of these pulleys in function of the variation of the length of reserve, means for changing the registered variations into displacements of the screw of the sector, two distinct cams, one of which is fixed on the axis of the faller, the other pivoting around a fixed point and leaning on the first cam, a roller in relation with one of the extremities of a lever connected with a 85 brake acting on one of the pulleys and leaning on the second cam, and a member in which is freely engaged the axis of the counter faller in order to prevent the swinging of the said member, this said member bearing 90 the said fixed point.

In testimony whereof I have affixed my signature.

JOSEPH DETHIER.
